UNITED STATES PATENT OFFICE.

GEORGE H. MINIER AND THADDEUS LOWE, OF SOUTH PASADENA, CALIFORNIA.

DESIGN FOR A HEATER-CASING.

40,979.

Specification for Design.

Patented Nov. 8, 1910.

Application filed August 27, 1910. Serial No. 579,356. Term of patent 14 years.

To all whom it may concern:

Be it known that we, GEORGE H. MINIER and THADDEUS LOWE, citizens of the United States, residing at South Pasadena, in the county of Los Angeles and State of California, have invented a new, original, and ornamental Design for a Heater-Casing, of which the following is a specification, reference being had therein to the accompanying drawing, forming part thereof.

The figure is a perspective view of the heater casing showing our new design.

Our design is a heater casing which is rectangular in shape and is provided at each end with a niche in which a pillar is placed.

The heater casing is trimmed at the top and bottom with longitudinally extending lines of beading, and the pillars are also trimmed with beading.

We claim—

The ornamental design for a heater as shown and described.

In testimony whereof we hereunto affix our signatures in presence of two witnesses.

GEORGE H. MINIER.
THADDEUS LOWE.
